UNITED STATES PATENT OFFICE

HERBERT GOULD BEEDE, OF PAWTUCKET, RHODE ISLAND

GARMENT PRESSING MACHINE

Application filed July 16, 1928. Serial No. 292,938.

This invention relates to a garment pressing machine of the class set forth in my Patent No. 1,661,153, March 6, 1928, and refers more particularly to the construction of the 5 pressing elements commonly known as the "buck and head" in which the buck is fixedly mounted upon a stationary support while the head is hinged to swing about an axis parallel with the longitudinal center of the 10 buck and head and some distance to the rear thereof to allow the garments to be conveniently manipulated across and upon the surface of the buck and around the marginal edges thereof preparatory to pressing.

15 These machines are adapted to be used more particularly by clothing manufacturers, tailors, dry cleaners and the like for pressing and shaping coats, vests, trousers, under-wear and various other articles of wearing 20 apparel which are brought to the machine in a more or less dry condition as distinguished from ironing machines in which the goods are submitted in a more or less moist condition but it will be obvious from the following 25 description that the same machine may be used for pressing and shaping various garments which are brought to the machine in a more or less wet or dry condition.

It is well-known that garments of various 30 weights, thicknesses or firmness require the application of different amounts of moisture in order that they may be rendered sufficiently soft and pliable for pressing, shaping and sterilizing when operated upon by the pressing elements of the machine and that when 35 operating upon light silks or materials having a sleazy texture or garment linings of similar weak texture considerable care must be taken not to oversteam or overheat such 40 materials and in order to afford a closer regulation of the application of steam and heat to garments of varying textures I have provided means whereby the steam and heat may be applied to the garment from either the 45 buck or the press-head or through both of the pressing elements simultaneously.

The main object is to simplify the construction of the pressing elements and at the same time to establish a more direct and easy flow of steam thereinto and therethrough for

heating and garment-steaming purposes than has heretofore been practiced.

One of the specific objects is to obtain a more direct application of the live steam to the garment for moistening purposes and at 55 the same time to reduce to a minimum the condensation of the steam in transit through either or both of the pressing elements by concentrating the distributing chamber and perforated wall thereof as nearly as possible 60 along the longitudinal centers of said elements and establishing a more direct connection between the steam inlets and distributing chambers.

Another object is to make the heating areas 65 of the pressure sides of the pressing elements considerably greater than the areas of the steam distributing chambers and exits and to arrange the steaming chamber and heating chamber of both elements in such manner 70 that the steam delivered to the steaming chambers will be more or less superheated by the heat from the heating chambers.

In other words, I have sought to extend the heating chambers across and some distance 75 beyond the marginal walls of the steaming chambers so as to afford a maximum heating area for not only superheating the steam delivered to the distributing chambers but also for applying a uniform heat to 80 all parts of the garment which may be brought into contact with the pressing elements during the pressing operation and thereby to effect not only a quick steaming but also a quick drying of the garment following 85 the steaming, pressing and shaping operations.

Another object is to simplify the means for removing the moisture and water of condensation from the pressing elements. 90

Other objects and uses relating to specific parts of the pressing elements will be brought out in the following description.

In the drawings:

Figure 1 is a top plan of the lower pressing 95 element or buck.

Figure 2 is a longitudinal sectional view of the same taken on line 2--2, Figure 1.

Figure 3 is a horizontal sectional view taken in the plane of line 3--3, Figure 2. 100

Figures 4 and 5 are detail sectional views taken in the planes of lines 4-4 and 5-5, Figure 3.

Figure 6 is a top plan, partly broken away, of the larger end of the buck showing more particularly the vacuum pocket and pipe connected thereto and also the deflector plate for deflecting the live steam across the pocket.

Figures 7, 8 and 9 are transverse vertical sectional views taken respectively in the planes of lines 7-7, 8-8 and 9-9, Figure 3.

Figure 10 is a top plan of the press head.

Figure 11 is a longitudinal sectional view taken in the plane of line 11-11, Figure 10.

Figure 12 is an inverted plan of the press head.

Figure 13 is a horizontal sectional view taken in the plane of line 13-13, Figure 11.

Figures 14, 15 and 16 are transverse vertical sectional views taken respectively in the planes of lines 14-14, 15-15 and 16-16.

The invention is directed more particularly to the construction of the pressing elements comprising a buck —1— and a press head —2— but it is to be understood that these parts will be supported in proper relation to each other for pressing coaction in a manner somewhat similar to that shown in my patent previously referred to so as to permit the head to swing toward and from the buck about an axis substantially parallel with the longitudinal center of the buck and some distance to the rear thereof to afford ample clearance for the manipulation of the garment upon and around the marginal edges of said buck preparatory to steaming, sterilizing, shaping and drying the garment in practically one and the same operation.

40 Buck

As illustrated the buck —1— comprises an elongated hollow body —3— of cast metal supported in a substantially horizontal position and relatively shallow vertically and having its opposite longitudinal edges tapered from one end toward the other end and its opposite ends rounded, the upper surface of said buck being convexed in cross section and substantially straight and horizontal along its longitudinal center.

The lower face of the buck is provided with longitudinally spaced bearing surfaces —4— along its longitudinal center adapted to rest upon a stationary support, not shown, and to be secured thereto by suitable clamping bolts entering threaded apertures —5— in the bearing portions —4—, Figure 2, said bearings —4— being located some distance from the sides and the opposite ends of the buck to distribute the weight and pressure more evenly along the longitudinal center of the buck and midway between the sides thereof.

The body section —3— is provided with lower and upper non-communicating steam-heating and steam-distributing chambers

—6— and —7—, both of which are relatively shallow vertically and extend the major portion of the length of the buck, the steam-heating chamber —6— being extended across the major portion of the width of the buck and beyond the marginal walls of the upper distributing chamber to serve the double purpose of heating the entire pressing area of the buck and also to superheat and thereby to reduce condensation of the steam in transit to and through the distributing chamber.

The lower and upper walls of the chamber —6— are united by a central lengthwise partition —8— for reinforcing purposes and also to form opposite lengthwise steam-circulating passages, the opposite ends of the partition being in spaced relation to the corresponding end walls of the chamber to form connecting passages for the adjacent ends of the lengthwise passages whereby the steam may circulate entirely around the partition and along the side and end walls of the chamber.

The lower and upper walls of the chamber —6— are also connected by integral stays —9— arranged in spaced relation at opposite sides of the partition for reinforcing purposes. The outer walls of the chamber —6— are mainly of uniform thickness and follow more or less closely the tapered and curved outlines of the sides and ends of the buck but are arranged a sufficient distance within said marginal edges to form a marginal flange —10— as a continuation of the top wall of the buck.

These flanges —10— serve as a convenient means for receiving the marginal edges of a pad or other foraminous covering which is usually drawn smoothly over the top surface of the buck and shirred or otherwise secured around and under the flanges —10—.

A portion of the bottom wall of the chamber —6— near the larger end thereof and preferably at the rear of the adjacent end of the partition —8— is depressed to form a well or sump —11— adapted to receive water of condensation which may accumulate in said chamber, the bottom of the well —11— being disposed in a plane some distance below the remaining portions of the bottom wall of said chamber and provided with a drainage outlet —12— adapted to be connected by a return pipe to the steam generator or to a waste pipe, as may be desired.

The bottom wall of the chamber —6— is also provided with opposite lengthwise channels —13— and —13'— adjacent the outer side wall of the chamber to extend the major portion of the length thereof between the opposite ends of the partition —8— and connected near the smaller end of the chamber by a cross channel —13''—, Figure 3.

These channels —13—, —13'— and —13''— also serve to receive and to drain the water of condensation from the cham-

ber —6— to the well or sump —11— and for this purpose the bottom of the channel —13— is slightly inclined downwardly from the larger end of the chamber to the cross channel —13''— which may also be inclined rearwardly to drain into the adjacent end of the rear channel —13'—.

This channel —13'— is inclined downwardly from the cross channel —13''— to the sump or well —11— into which it is adapted to discharge any water of condensation which may accumulate in the channels so that the well forms a common receptacle for all of the water of condensation within the chamber —6— while the outlet pipe —12— affords a simple and convenient means for draining the water from the chamber.

In this manner a continuous supply of live steam may be maintained in the chamber —6— for heating the entire buck and also for superheating the steam in transit to the distributing chamber —7— for garment moistening purposes or at least assisting in maintaining a maximum temperature of the garment moistening steam.

The drainage outlet pipe —12— extends through and some distance above the bottom of the well —11— but terminates below the remaining portions of the bottom wall of the chamber —6— to assure the retention of a limited quantity of water in the well to form part of a steam trap, presently described.

A baffle plate —14— is integrally united to the end of the partition adjacent the larger end of the buck and to the top wall and rear wall of the chamber —6— to extend across the top of the well —11— and downwardly into said well below the level of the upper end of the drain pipe —12— but in spaced relation to the bottom of the well so as to cooperate with the upper ends of the drain pipe —12— in forming the steam trap, previously mentioned, see Figures 3, 4 and 5.

That is, the portion of the bottom wall of the steam chamber —6— between the well —11— and larger end of the buck at the rear of the longitudinal center of said buck is provided with a steam inlet —15— for directing steam from the source of supply to the interior of said chamber between the larger end wall of the chamber and adjacent end of the partition —8—, the baffle plate —14— and body of water in the well —11— serving to prevent the passage of the steam directly from the inlet into the chamber at the rear of the partition thereby causing the steam to pass from the inlet across the adjacent end of the partition —8— and thence through the chamber along the front side of the partition and around the other end thereof to return through the chamber at the rear of the partition to the well —11— where the steam may or may not be condensed to re-

turn to the boiler through the drain pipe —12— thereby maintaining a supply of live steam throughout the area of the chamber —6— and at the same time removing the moisture of condensation as it is formed.

The central portion of the bottom wall of the chamber —6— is also provided with a relatively shallow pocket or passage —16— extending under the adjacent portion of the partition to connect the steam passages at opposite sides thereof and to allow some of the steam to pass therethrough but the formation of this pocket is due primarily to the means for uniting the core sections which form the passages at opposite sides of the partition and while it is incidental to the method of molding the buck it is not in any way detrimental to the circulation of the steam throughout the area of the chamber —6— along opposite sides of the partition.

The upper steam distributing chamber —7— is relatively narrow transversely and extends along the longitudinal center of the top of the buck the major portion of the length thereof, but terminates within the end walls of the lower chamber —6—, said distributing chamber —7— being provided with a perforated top wall —17— which conforms to the transverse and lengthwise contour of the upper surface of the buck and serves to admit steam to the garment thereon for moistening purposes or when covered with a pad permits the steam to pass through the pad to the garment.

The distributing chamber —7— and perforated top wall thereof are substantially straight from end to end, the perforated top wall —17— being preferably made of thin sheet metal or equivalent material of slightly greater area than the chamber —7— so that its marginal edges project beyond the marginal walls of the chamber and in order that the upper surface of the perforated plate —7— may be substantially coincident with the upper surfaces of the remaining portions of the buck the upper faces of the marginal walls of the chamber —6— are recessed at 18 to correspond to the thickness of the adjacent portions of the plate —17—.

When the plate —17— is placed in operative position with its marginal edges seated in the bottoms of the recesses —18— it is held against endwise or lateral displacement by the end and side walls of said recesses and is also held against upwardly displacement by fastening screws —19— along the marginal edges thereof and engaged in threaded apertures in the underlying portions of the buck, the heads of the screws being counter-sunk so that their upper faces are substantially coincident with the upper face of the plate —17—.

The intermediate portions of the perforated plate —17— overlying the chamber —7— are supported by stays —20— which are preferably formed integral with the bot-

tom wall of the chamber and are arranged in spaced relation to each other and to the side and end walls of the chamber to allow free circulation of the steam through said chamber and out through the perforations in the top wall thereof.

Steam is admitted from a source of supply to the distributing chamber —7— through a suitable inlet —21— in the bottom of said chamber between the larger end of the buck and adjacent end of the partition —8—, as shown in Figures 2 and 3, said inlet being made in the form of a pipe having its upper end extended through an opening in the adjacent portion of the bottom of the heating chamber —6— and across said heating chamber and is adapted to be connected to a source of steam supply in any well-known manner, not necessary to herein illustrate or describe, said pipe being provided with a nut —22— and a packing —22'— adapted to engage the underside of the adjacent portion of the buck to prevent leakage of steam from the heating chamber through the adjacent pipe opening.

25 The end of the partition —8— nearest the larger end of the chamber —7— is widened or extended laterally limited distances to opposite sides of the longitudinal center of the buck to permit the formation of a suction or 30 vacuum channel —23— in the upper portion thereof.

That is, the portion of the bottom of the steam-distributing chamber —7— adjacent the wider portion of the partition —8— is depressed below the upper surface of the remaining portion of the bottom wall to form the suction channel —23— which extends lengthwise of the partition and is provided at its lowest point with a suction outlet —24— 35 adapted to be connected by a pipe —24'— to any suitable suction device for withdrawing steam and moisture from the chamber —7— and from the superposed pad and garment which may rest thereon.

40 The bottom wall of the channel —23— is preferably inclined upwardly from the suction outlet —24— toward the smaller end of the buck to merge with the upper face of the lower wall of the remaining portions of 50 the chamber —7— some distance from the outlet —24—, as shown in Figure 2.

55 A deflector plate —25— is secured at one end to the bottom wall of the distributing chamber —7— nearest the deeper end of the channel —23— and has its opposite end extended lengthwise of and above said channel but in spaced relation to the corresponding end and bottom thereof directly over the suction outlet —24— for directing the steam admitted to the chamber —7— through the inlet —21— across the upper end of the suction outlet —24— and channel —23— and also causing the suction to be distributed 60 more evenly or uniformly throughout the en-

tire area of the chamber —7— when the suction device is in operation.

When using the buck for garment moistening and drying purposes the live steam from the source of supply is permitted to enter the heating chamber —6— continuously through the inlet —15—, the steam being allowed to pass from said inlet through the chamber at the front side and around the rear end and rear side of the partition —8— to the well —11— thereby supplying the heating agent to practically all parts of the heating chamber from end to end and from side to side, the water of condensation being continuously drawn off through the drainage outlet —12— and may be returned to the boiler, if desired.

70 The steam pipe as —21— for supplying steam to the distributing chamber —7— for garment moistening purposes may be provided with any suitable valve, not necessary to herein illustrate or describe, for permitting intermittent flow of the steam to the distributing chamber when and as may be desired during which operation the steam will flow from the inlet the entire length and breadth of the distributing chamber —7— and thence through the perforations in the top wall —17— to the overlying pad or garment for moistening the latter preparatory to pressing and shaping.

75 When the garment has been moistened, pressed and shaped, suction from any source may be produced in the suction outlet —24— and chamber —7— for withdrawing steam from said chamber and also from the pad and from the garment resting thereon to expedite the drying of said pad and garment thus permitting the latter to be put on and worn immediately following the pressing and shaping 80 operation.

85 Any of the well-known forms of suction devices such as fans, ejectors, piston and rotary pumps and the like may be used to produce the desired suction in the chamber —7— through the outlet —24— but it is equally obvious that the suction device may be substituted by a blower of any well-known type for blowing air through the conduits —24'— and —24— into the chamber —7— and thence 90 through the pad and garment for displacing the moisture therefrom by air pressure rather than by suction and, therefore, I do not wish to limit myself to the use of any particular suction or air pressure device.

Press head

100 The press head —2— is elongated and tapered longitudinally in one direction to conform approximately to the outline of the buck and preferably consists of a hollow body of cast metal having its lower face concave transversely complementary to the transversely convexed upper surface of the buck so as to produce more or less of a transverse stretching effect upon the garments when sub-

jected to pressure by the movement of the head into pressing coaction with the buck.

This press head is provided with upper and lower non-communicating steam-heating and steam-distributing chambers —26— and —27— which are relatively shallow vertically and extend the major portions of the length of the head.

The chamber —26— is extended transversely and longitudinally some distance beyond the corresponding side and end walls of the chamber —27— which is relatively narrow transversely but straight longitudinally and is provided with a perforated bottom wall —28— through which steam is adapted to be discharged to the garment under treatment for moistening purposes, the length and transverse width of the chamber —27— and perforated plate —28— being approximately equal to the corresponding dimensions of the chamber —7— and perforated plate 17 of the buck so as to register therewith when the press head is brought into pressing coaction with the buck.

The lower marginal edges of the press head —2— are flanged outwardly at —29— to form continuations of the lower concave pressing surface and are adapted to receive a foraminous or a steam pervious cover or press cloth which is stretched across the lower face of the head and its opposite edges drawn around the flanges —29— and shirred or otherwise secured in operative position when it is desired to avoid the imprints of the perforations on the garment.

The perforated plate —28— is preferably made of sheet metal and of slightly greater length and width than the corresponding length and width of the chamber —27— so that when placed in operative position its marginal edges will extend beyond the side and end walls of the chamber and in order that the lower surface of the perforated plate may be substantially coincident with the adjacent portions of the bottom of the head the lower surface of the marginal walls of the chamber —27— are recessed to a depth corresponding to the thickness of the plate so that its side and end walls will be of substantially the same length and width as the plate which has its marginal edges seated in the recess and secured thereto by suitable fastening means as screws as —30—, Figure 12.

The top wall of the chamber —27— is provided with a series of integrally spaced stays —31— arranged in spaced relation for engaging and supporting the intermediate portions of the perforated plate in operative position.

As previously stated, the heating chamber —26— extends across and beyond the marginal walls of the steam-distributing chamber —27—, the bottom wall of said heating chamber being convexed transversely for draining

the water of condensation therefrom particularly when the head is rocked upwardly and rearwardly from its pressing position at which time any water of condensation which may be lodged on the transversely convexed lower wall of the chamber —26— will flow to the lower rear side of the chamber where it is free to escape through a drainage outlet —32—.

The drainage pipe —32— is secured in an opening in the rear side wall of the chamber —26— near the larger end of the head and may be connected to and may constitute a part of the return connection to the boiler either through the medium of a flexible pipe or a hinge joint coaxial with the axis of movement of the head, it being understood that when the head is raised or rocked upwardly from its pressing position the rear side of the larger end thereof will be considerably lower than the corresponding side of the smaller and by reason of the lengthwise taper of the buck thereby facilitating the discharge of water of condensation from all parts of the chamber —26— to the drainage outlet —32—.

A steam inlet pipe —33— leading from any suitable source of supply is secured in an opening in the rear wall of the chamber —26— near the smaller end of the press head, as shown in Figures 12 and 13, which supply live steam to said chamber for heating purposes.

The steam pipe —33— may be connected to the source of supply through the medium of a flexible connection or may be provided with a hinge joint coaxial with the axis of movement of the press head and inasmuch as these connections form no part of my present invention it is believed to be unnecessary to herein illustrate or describe the same.

The lower and upper walls of the heating chamber as —26— are united by integral webs or stays —34— and —34'— for reinforcing purposes, the stays —34— being elongated longitudinally of the head and inclined rearwardly from the small end toward the large end of the head so that when the head is raised any water of condensation which may lodge against the webs will be deflected rearwardly toward the large end of the head to collect in the lower portion of the chamber at the drainage outlet —32—.

Steam is supplied to the distributing chamber —27— through an inlet pipe —35— which extends through an opening in the top wall of the heating chamber —26— entirely across said chamber and is secured at its lower end in a suitable opening in the bottom of the chamber —26—, said pipe being preferably located in the longitudinal center of the head and approximately midway between its opposite ends for distributing the steam evenly to all portions of the distrib-

uting chamber —27— as shown more clearly in Figure 11.

The steam pipe —35— may be connected in any well-known manner to a source of steam supply through the medium of a flexible pipe or through a hinge joint coaxial with the axis of movement of the press head and will be provided with a suitable valve operable at will to control the flow of steam to the chamber —27— and thence through the perforated bottom plate —28— to the underlying garment, the construction and operation of the valve for controlling the admission of steam to the chamber —27— being well-known and, therefore, unnecessary to herein illustrate or further describe.

The upper surface of the top wall of the heating chamber —26— is provided with suitable seats —36— in longitudinally spaced relation along the longitudinal center thereof for receiving the adjacent ends of a vertically movable supporting arm similar to that set forth in my patent previously referred to, the adjacent ends of the supporting arms being secured to the seats —36— by suitable bolts or screws entering apertures —37— in said seats as shown in Figure 10.

It will be noted that the live steam enters the smaller end of the heating-chamber —26— and is, therefore, free to expand toward the larger end without material resistance except through contact with the stays —34— and —34'— which, however, serves to increase the distribution of the steam more evenly over the entire area of the chamber and facilitate the passage of the water of condensation to the outlet —32— leading from the larger end of the chamber.

Referring again to the buck, Figure 6, shows an angular baffle rib —21— integral with the bottom wall of the distributing chamber —7— and projecting across said chamber to the underside of the perforated plate —7—, said baffle rib being extended forwardly from the rear wall of the chamber —7— between the adjacent end of the steam inlet pipe —21— and adjacent outer end wall of said chamber and thence longitudinally directly in front of the adjacent end 50 of the steam inlet —21— to terminate in spaced relation to the adjacent end of the channel —23— for directing the inflowing live steam from the supply pipe —21— along the chamber —7— toward the smaller end 55 thereof and across the upper surface of the deflector plate —25—.

The area of the distributing chamber —7— and —27— and their respective perforated plates —17— and —28— of the buck and head is considerably less than half the area of the pressing surfaces of their corresponding pressing elements, the object of which is to concentrate the passage of the garment-moistening steam through the buck and head along straight and narrow paths so that when

liberated at the exits of the perforations for moistening the garment it will be practically free from moisture of condensation by reason of its rapid transit through and distribution from the head to the garment thereby reducing to a minimum the liability of over saturation of the garment with moisture and at the same time conserving the use of the steam.

It will also be noted that the portions of the perforated steam-distributing plates of both the head and buck directly over the steam inlets are imperforate so that these imperforate portions may act as deflectors for the inflowing steam to cause it to be more evenly distributed throughout the area of the perforated portions.

I claim:

1. In a garment pressing machine, a longitudinally tapered press head hinged to swing upwardly and rearwardly from its pressing position about an axis parallel with its longitudinal center and provided with a steam receiving chamber having a drainage outlet near its larger end, the lower and upper walls of said chamber being connected by spaced lengthwise webs having their front faces inclined rearwardly toward the larger end of the head for draining the water of condensation toward said outlet when the head is raised.

2. In a garment pressing machine, a buck having non-communicating steam-chambers one above the other, the upper chamber having a perforated top wall and a depressed channel in its bottom wall, means for supplying steam to both of said chambers, the steam inlet for the upper chamber being located at one end of the channel, and a suction pipe connected to said channel for withdrawing steam from the upper chamber.

3. A garment pressing machine as in claim 2 in which the bottom of the upper chamber is provided with a deflector plate extending from the end of the channel nearest the steam inlet across the mouth of said suction pipe in spaced relation to the other end of the channel.

4. In a garment pressing machine, a buck having non-communicating steam-chambers one above the other, the upper chamber having a perforated top wall and a depressed channel in its bottom wall, the lower and upper walls of the lower chamber being connected by a central lengthwise partition extending the greater portion of the length of said chamber and its opposite ends in spaced relation to the corresponding ends of the chamber, said channel being extended downwardly into the partition, separate steam supply pipes discharging directly into said chambers, and a suction pipe connected to said channel.

5. In a garment pressing machine, a buck having non-communicating steam-chambers

one above the other, the upper chamber having a perforated top wall, a partition uniting the lower and upper walls of the lower chamber midway between its side walls and extending the major portion of the length of said chamber with its ends in spaced relation to the corresponding end walls of the chamber, the upper chamber having an outlet extending through the partition and bottom wall of the lower chamber and adapted to be connected to a suction device, and separate steam supply pipes discharging respectively into the upper chamber and into the lower chamber at one end of the partition.

6. In a garment pressing machine, a buck, a pressing element having non-communicating lower and upper steam chambers, the upper chamber having a perforated top wall, a partition uniting the lower and upper walls of the lower chamber and extending the major portion of the length and midway between the side walls thereof and its ends in spaced relation to its corresponding end walls of the chamber, a portion of the bottom wall of said lower chamber being depressed below its remaining portions to form a well, a baffle plate uniting the partition to the top wall and one of the side walls of the lower chamber and projecting into said well in spaced relation to the bottom thereof, a drainage pipe secured to and projecting above the lower edge and at one side of the baffle plate, means for introducing steam into the lower chamber in a plane above the upper end of the drain pipe and at the other side of said baffle plate, and means for supplying steam to the upper chamber.

7. In a garment pressing machine, a buck having lower and upper non-communicating steam-receiving chambers, and a central lengthwise partition dividing the lower chamber into opposite lengthwise steam-passages and provided with an exhaust opening leading from the upper chamber through the bottom of the buck.

8. In a garment pressing machine, a buck having lower and upper non-communicating chambers, a central lengthwise partition dividing the lower chamber into opposite lengthwise passages extending around both ends of the partition, and means for introducing steam into both of said chambers at one end of the partition, said partition being provided with an exhaust opening leading from the upper chamber through the bottom of the buck.

In witness whereof I have hereunto set my hand this 25th day of June, 1928.

HERBERT GOULD BEEDE.
